(57) **CLAIM**

The ornamental design for a curtain, as shown and described.

DESCRIPTION

FIG. 1 is a perspective view of a curtain showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof;

FIG. 9 is an enlarged view of the encircled portion in FIG. 1 thereof;

FIG. 10 is another enlarged view of the encircled portion in FIG. 1 thereof;

FIG. 11 is an enlarged view of the encircled portion in FIG. 2 thereof; and,

FIG. 12 is a perspective view of the curtain as it would be positioned during opening.

The broken lines depict portions of the article that form no part of the claimed design.
